(57) **CLAIM**

I claim the ornamental design for a smartwatch container with label, as shown and described.

DESCRIPTION

FIG. 1 is a top right front perspective view of a smartwatch container with label.

FIG. 2 is a front elevational view thereof.

FIG. 3 is a rear elevational view thereof.

FIG. 4 is a right side elevational view thereof, the left side elevational view being a mirror image thereof.

FIG. 5 is a top plan view thereof; and,

FIG. 6 is a bottom plan view thereof.

The shading lines shown in the drawings represent the approximate three-dimensional contour of the design, and are not intended to indicate surface decoration.
